UNITED STATES PATENT OFFICE.

ROBERT NEIL WILLIAMS, OF NORWICH, ENGLAND, ASSIGNOR TO POWERS ACCOUNTING MACHINE COMPANY, OF NEW YORK, N. Y., A CORPORATION OF DELAWARE.

PERFORATING-MACHINE.

1,309,927.

Specification of Letters Patent. Patented July 15, 1919.

Application filed November 10, 1917. Serial No. 201,227.

To all whom it may concern:

Be it known that I, ROBERT NEIL WILLIAMS, a citizen of the United States of America, residing in Norwich, England, have invented certain new and useful Improvements in and Relating to Perforating-Machines, of which the following is a specification.

This invention relates to improvements in perforating machines designed more particularly for use in the perforation of cards for tabulating and like machines, which cards are divided into a number of fields, such fields representing the various data or matters concerned.

In use the cards are passed through a tabulating machine with which are associated counters, whereby the value represented by the various perforations in each field in successive cards are added together.

Hitherto in machines for producing records in the form of perforated cards or the like, although provision has been made for producing a perforation or series of perforations consequential to the operation of keys for producing other perforations the consequential perforations have borne an immutable relation to the key or keys operated.

The present invention has for its object to provide for the controlling of the punches for the consequential perforations in a manner such that their production or non-production instead of bearing an immutable relation to the keys actuated, shall be dependent upon certain laws the fulfilment or non-fulfilment of which shall control the production of the consequential perforations. In other words while the operation of a certain key or keys for the main punches also prepares or sets the punch for the formation of the consequential perforation the operation of another key or other keys may neutralize the first setting and either permit or prevent the operation of the said punch for the formation of the consequential perforation accordingly as the requirements of the basic law are or are not fulfilled.

As an example of the application of the invention, assuming it is desired to take a census of the population of a country and at the same time to ascertain the number of persons qualified to vote, and assuming this census to be made in the United States of America, the returns would have to be ex-

amined to ascertain whether the individual were, for instance, a male twenty-one years of age or over, of native birth or naturalized, not a pauper unless a veteran, and not mentally unfit. Under these circumstances the mental operation necessary to determine the qualified from the unqualified would have to be repeated a great number of times, say 110,000,000. By means of the present invention the operator will, in recording the facts appropriate to each individual, automatically record the fact that such individual is or is not qualified to vote. The operating surfaces on the main punch setting slides are so arranged that a consequential setting of the qualifying punch is automatically secured. Thus for example assuming the punch controlling slides to have been set to produce a perforation consequent upon the recording by the operator of the facts that the individual is white, naturalized, not a pauper, twenty-one years of age or over. The facts so far recorded are in favor of the individual being qualified to vote. If, however, the fact is next recorded that the said individual is an idiot, the setting previously given to produce a perforation by the "voting" punch is altered, and no perforation will be made.

In order that the invention may be the better understood, drawings are appended illustrating the application of the invention, for the purpose of preparing a census as just described, to a perforating machine such as forms the subject of my Patent, No. 1,086,397, issued February 10, 1914.

In the accompanying drawings:—

Figure 1 is a side elevation partly in section showing the invention applied to a known type of punching machine.

Fig. 2 is a plan to a larger scale of certain parts showing their relation to the slides.

Fig. 3 is a sectional view taken on line AA Fig. 2.

Fig. 4 is a similar view on line BB Fig. 3.

Fig. 5 is a view showing more or less diagrammatically of the working of the parts.

In the drawings in which only such parts of the main portion of the machine are illustrated as are necessary for the proper understanding of the invention, 1 indicates settable slides carried in plates 2, 3. The

positioning of the slides is effected by means of levers 4 which engage the inner ends of the slides 1 as shown and which levers themselves are actuated by means of the sliding finger plates or slides 5. The slides are each provided upon their underside or edge with a projection 6, which when the slide is set is brought over the particular punch 7 which it is desired shall be rendered effective. The cards are contained in a magazine 8 from which they are fed by a slide 9 and from which they pass on to a perforated plate 10 disposed beneath the punches and carried by a vertically reciprocating frame 11. As the frame 11 rises the card indicated by *x* will be raised with it and be perforated by the particular punch which is prevented from rising by the aforesaid projection 6. Mounted upon the guide 20 plate 12 for the punches in any suitable manner is a plate 12^a.

The arrangement and setting of the said slides and the operation of the punches is as described in my Patent No. 1,086,397, issued 25 February 10, 1914. Arranged to slide vertically within perforations formed in a plate 12^a in which they are mounted in any suitable manner such that their rotation is prevented, are plugs indicated respectively by 30 13, 14, 15, 16, 17 and 18, each of said plugs at their lower ends being in engagement with the upper edge of a slide 1 which slide controls the operation of the punches 7. The plugs 13 and 14 register with the "age" 35 recording row of punches, the plug 15 with the "pauper" recording row of punches, the plug 16 with the "veteran" recording row of punches, the plug 17 with the "idiot" recording row of punches, and the plug 18 with 40 the "alien" recording row of punches. To reduce friction at the point of contact of the plugs with the slides said plugs are preferably provided with rollers 19. The plugs just referred to are each provided at their 45 upper ends with an inclined surface as shown in Fig. 3 which surfaces are adapted to engage correspondingly inclined surfaces, the purpose of which is hereafter more fully described, provided upon a horizontally 50 disposed slide indicated by 20 mounted upon the aforesaid plate 12^a and which slide is held against vertical displacement by a plate 21 beneath which the slide is freely movable. The plugs 13 to 18 are controlled 55 by means of inclined surfaces formed upon the upper edges of the aforesaid slides 1 which slides and plugs, as shown upon the drawings, represent the various qualifications or disqualifications which govern the 60 capacity or otherwise of the person dealt with to the right to vote. In addition to the aforesaid punches 7 there is provided a punch 22 controlled by means of the extension 23 by the aforesaid slide 20. The punch 65 just referred to for the purpose of identifica-

tion is hereafter referred to as the "voter punch." Slidably mounted upon slide 20 by means of the pins 23^a projecting from the side of the plate 20 and passing through slots 24 is a plate formed in two parts *x* *y* 70 one resting upon the other. The plates just referred to are connected by a spring 25 the tendency of which is to hold the plates *x* *y* together, and in a position such that the pins 23^a are normally in the position shown 75 in Fig. 3. The plates *x* *y* are however capable of independent motion so that when required as will be hereafter explained the upper plate *y* may be pushed backward against the action of the spring 25 to permit the slide 20 to be drawn back by its spring 26. It will be understood that the spring 25 is stronger than the spring 26 provided for effecting the return of slide 20. A stop or abutment 27 is provided on plate 80 *x* to limit the movement of the upper plate *y* under the action of spring 25. The backward movement of plate *y* is effected by means of the plug 16. A spring 28 is provided to return plates *x* and *y*. A stop 50 85 on the plate *x* coöperating in the slot 51 90 formed in the plate 12^a, is provided to limit the extent of movement of plate *x* under spring 28.

The voter punch 22 will punch a hole 95 registering a qualified voter if the movement of the pin 23 is blocked by the slide 20 when the card is lifted, that is unless the recess 29 adjacent to the end of the slide is in position so as to give the pin 23 a free upward passage. The slide 20 is normally retained by its spring 26, in a position that the pin 23 is so blocked and such that the inclined surfaces 30, 31, 32 of such slide 20 abut against the inclined surfaces 33, 37, 38 of the plugs 100 13, 17 and 18 respectively as shown in Fig. 3. The surfaces 39 and 40 are formed upon projections respectively upon the main slide 20 and plate *y* while the surface 41 is formed upon the inner ends of plates *x* *y*, the remaining surfaces are upon the slide 20. The plugs 13 to 18 are lifted by the configuration of the upper surfaces of the punch slides 1 which surfaces are shown and identified by the numerals 42 to 47, in Figs. 5, 4, and the 115 different positions of which slides correspond to the lines 0 to 9.

When, during the perforation of a card, any one or more of the descriptions alien, idiot, pauper, or minority apply, the slide 120 20 is moved over to clear the pin 23 so that the veteran punch 22 will not be actuated in the ensuing cycle of operation to produce a perforation. If merely the pauper description applies, the motion ordinarily transmitted may be neutralized when in addition thereto the veteran description applies.

Taking first the age punches when the movement of the slide having the surface 42 representing the tens of age, brings the 0 130

position of said slide under the plug 13, the projection 6 is over the punch 0 so rendering said 0 punch effective. The plug 13 is raised at positions 0 and 1 and indicates that those persons less than 19 years of age have no vote, in other words the voter punch is non-effective. In position 2 the elevation is only one half the total amount, the effect of which is that for people in the twenties the tens slide does not take away the vote unless the unit slide having the surface 43 is in the position 0. On the forward movement of the slide 20 by the plug 13 as aforesaid the projection carrying surface 39 Figs. 4 and 5 has been brought over the vertical plug 14 and consequently the slide 20 for the individuals of 20 years will receive half of its movement from the tens plug 13 and the other half from the units plug 14. By this combination, ages in the thirties and above would not cause the slide 20 to move at all, since the plug 14 would miss the surface 39. The slide 20 when actuated for persons between 21 and 29 will only have a half motion, which would not free the upward passage of pin 23. Should, however, the plug 15 (pauper) be raised, it will engage the inclined surface 41 on the plate α and push the plate α to the right and by means of the spring 25 also carry the plate γ to the right. At the same time the plate 20 by reason of the pin and slot connection between it and the plate γ will also be moved in the same direction unless the slide 20 were already locked by the plugs 13 and 14. The spring 25 is under tension but as already explained it is strong enough to overcome the power of the spring 26 against which it is pulling by reason of the aforesaid connection, between plate γ and plate 20. If, however, the plug 13 (veteran) is raised, it will come into contact with the inclined surface 40 on plate γ and the movement of plate α being prevented by the previously raised pauper plug 15 the said plug 16 will push the plate γ to the left against the action of spring 25 allowing spring 26 to draw the slide 20 backward accordingly as its return is or is not prevented by the raising of any other plug, age 13 and 14, idiot or alien. When the "pauper" and "veteran" plugs have operated movement of the slide 20 is therefore controlled by other considerations such as age, mental incapacity and nationality.

Obviously the arrangement may be such as to produce a perforation corresponding to

any desired combination of perforations in any of the fields.

Claims:

1. In a perforating machine means for the production of secondary perforations which are consequential to the setting of certain punches for producing main or primary perforations, means whereby the setting of the punch for producing the secondary perforations may be altered in consequence of the setting of other punches for producing primary perforations, whereby the formation of the secondary perforation is controlled by a plurality of settings of the primary punches. 60 65 70

2. In a perforating machine means for the production of secondary perforations which are consequential to the setting of certain punches for producing main or primary 75 perforations, comprising a series of primary punches, a secondary punch, settable slides controlling the primary punches, a second slide controlling the secondary punch, means operated by the slides of the primary 80 punches to operate the slide of the secondary punch whereby the formation of the secondary perforation is controlled by a plurality of settings of slides for the primary punch. 85

3. In a perforating machine means for the production of secondary perforations which are consequential to the setting of certain punches for producing main or primary 90 perforations, comprising a series of primary punches, a secondary punch, settable slides controlling said primary punches, cam surfaces upon said primary punch slides, vertically disposed bodies, designed to engage the cam surfaces, inclined surfaces 95 upon said vertically disposed bodies, a slide having inclined surfaces designed to engage the surfaces on the vertically disposed bodies, a secondary punch controlled by the aforesaid slide, the cam surfaces on the 100 slides and the surfaces upon the vertical bodies and upon the punch controlling the secondary slide being so related that the formation of the secondary perforation is controlled by a plurality of settings of the 105 primary punches.

In testimony whereof I affix my signature in the presence of two witnesses.

ROBERT NEIL WILLIAMS.
